CLAIM

The ornamental design for a dresser and chair set, as shown and described.

DESCRIPTION

FIG. 1 is a first perspective view of the dresser portion of the dresser and chair set showing my new design;

FIG. 2 is a second perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof;

FIG. 8 is a bottom view thereof;

FIG. 9 is a perspective view of the dresser portion of the dresser and chair set, in an alternate configuration;

FIG. 10 is a first perspective view of the chair portion of the dresser and chair set showing my new design;

FIG. 11 is a second perspective view thereof;

FIG. 12 is a front view thereof;

FIG. 13 is a back view thereof;

FIG. 14 is a left-side view thereof;

FIG. 15 is a right-side view thereof;

FIG. 16 is a top view thereof;

FIG. 17 is a bottom view thereof;

FIG. 18 is a perspective combination view of the dresser and chair of the dresser and chair set; and,

FIG. 19 is a perspective combination view of the dresser and chair of the dresser and chair set in an alternate configuration.

The broken lines shown in the drawings depict portions of the dresser that form no part of the claimed design.

1 Claim, 19 Drawing Sheets
